CLAIM

The ornamental design for a dustpan, as shown and described.

DESCRIPTION

FIG. 1 is a top, front and right side perspective view of a dustpan showing my new design;

FIG. 2 is a top, rear and right side perspective view thereof;

FIG. 3 is a front and left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is another top, front and right side perspective view thereof; and,

FIG. 11 is another front and left side perspective view thereof, shows that a handle is mounted over the design. The broken lines in the Figures depict environment only and form no part of the claimed design.
